UNITED STATES PATENT OFFICE

104,422

DESIGN FOR A RING OR SIMILAR ARTICLE OF JEWELRY

Felix P. Kinsley, St. Louis, Mo.

Application February 27, 1937, Serial No. 67,909

Term of patent 14 years

To all whom it may concern:

Be it known that I, Felix P. Kinsley, a citizen of the United States, residing at the city of St. Louis, State of Missouri, have invented a new, original, and ornamental Design for a Ring or Similar Article of Jewelry, of which the following is a specification, reference being had to the accompanying drawing, forming part thereof.

The drawing is a perspective view of a ring showing my design. The dominating feature of

my design for a ring resides in the form of the element which, as shown in the drawing, forms a base for the initial, and its arrangement with the other features of the design. The said element may be metal, a cameo, a precious or semi-precious stone or the like.

I claim:

The ornamental design for a ring or similar article of jewelry as shown and described.

FELIX P. KINSLEY.
